WILLIAM B. LODGE AND HIRAM PLATNER, OF DANBURY, CONNECTICUT.

Letters Patent No. 71,516, dated November 26, 1867.

IMPROVEMENT IN FELTING-MACHINES.

The Schedule referred to in these Letters Patent and making part of the same.

TO ALL WHOM IT MAY CONCERN:

Be it known that we, WILLIAM B. LODGE and HIRAM PLATNER, both of Danbury, in the county of Fairfield, and State of Connecticut, have invented a new and useful Improvement in Felting-Machines, of which the following is a full, clear, and exact description, reference being had to the accompanying drawing, forming part of this specification, and in which—

Figure 1 represents a plan of a machine constructed according to our improvement, and

Figure 2 a vertical section of the same.

Figure 3 is a diagram in illustration of a modified construction of certain parts.

Similar letters of reference indicate corresponding parts.

This invention aims at imitating, but in a more perfect manner, and by automatic or mechanical means, the hand process of felting, by using a reciprocating rolling motion, which, in practice, is found to be more effective than a continuous rolling motion of the goods between endless aprons. In this connection, it may be observed that this, our improvement, is superior to the old-fashioned hand-motion in the following, among other respects, namely, by it the felting may be done in hotter water, and with greater weight or pressure, both of which contribute to produce a firmer or harder felt, and to accomplish the felting quicker.

The invention is more particularly designed to felting hats or hat-bodies, and the nature of it consists in the combination of a holding-apron or aprons, with a vibratory rubbing-board or boards, in such manner that the article to be felted is effectually retained in such position, with reference to the boards by which it is acted upon, as to secure, in an automatic manner, an effectual and rapid felting of the goods. Also, so that the body or bodies being felted are, in the course of such operation, worked in and out of a hot-water bath or its contents. And furthermore, the invention consists in a peculiar combination of devices for controlling the action of the felting-board or boards, both as regards release of the goods and adjustment of the aprons in which they are worked.

Referring to the accompanying drawing, figs. 1 and 2, in which the machine is represented as double, that is, constructed to allow of felting being conducted by separate hands on opposite sides of one machine, and with a duplicate arrangement of felting-boards to each hand, though such an arrangement may be indefinitely extended, or the machine, if desired, be made for a single set of felting-boards—

A is the frame of the machine, which may be constructed in any suitable manner, and made to carry a driving-shaft, B, driven by any suitable power, and operating by means of eccentrics, *a*, (one to either pair of opposite rubbers,) and rods, *b*, levers, C, which serve to give a reciprocating or vibratory motion to the upper felting-boards D, pivoted, as at *c*, to the levers C. These boards are arranged at a suitable distance over an inclined board or boards, E, that may be described as forming the sides of a hot-water vat or bath, F, and have attached to them, at their forward ends, an apron or aprons, G, made of any suitable material, or combination of materials, and extended so as to constitute a pocket for the goods to be felted, and secured to the inclined boards E, or to a roller or rollers, *d*, below the same, and held in check by ratchet-wheels *e* and pawls *f*, to regulate the length of apron to different quantities or kinds of work. If desired, the lower boards E may also be constructed to have a reciprocating or vibratory motion. The boards D may have the requisite pressure or weight given to them by means of weights, *g*, and be lifted, when it is necessary to release the goods, by treadles, *h*, cords or straps, *i*, and levers, *j*, a counterbalance-weight, *k*, being preferably attached, to lift either board D when relieved of its weights.

In the operation of a machine constructed as represented and described, the goods to be felted may, after being formed into a roll, be first inserted into the pockets formed by the aprons G, and after being reciprocated or vibrated in a rolling manner between the boards D and E, in and out of the hot water in the bath or vat F, for a sufficient interval of time, be subsequently acted upon in a similar manner, but under a heavier pressure, by wrapping them round a roller, *s*, for "finishing off," and which provides hard surfaces to work both sides of the felt, and admits of the felt being finished harder and smoother. The felting-boards on opposite sides of this double machine are, or may be, worked totally independent of each other for performing work under different stages of progress. A single attendant may work two sets of felting-boards on one side of the machine, and attend to the "crozing" of a third set of goods, preliminarily to exposing or subjecting them again to the action of the felting-boards. By the treadles *h* he may at pleasure, or when it is desired to take out a roll, sufficiently

lift or tilt the boards D, so as to cause the aprons or pockets G to deliver said roll out of the water in the vat, and so that the same may readily be caught and removed.

As a modification of the construction herein described, the reciprocating felting-boards may be arranged to work vertically, in combination with an intermediate reciprocating board, united to them by the aprons or pockets, arranged to pass over suitable pulleys, and carrying the goods to be felted, substantially as represented by red lines in fig. 3.

What is here claimed as new and useful, and desired to be secured by Letters Patent, is—

1. The combination of the boards D and E, one or both having a reciprocating motion, as described, with an apron or pocket, G, for holding the goods to be felted, arranged and operating substantially as specified.
2. The combination, with the felting-boards D and E, and apron G, of the take-up or adjusting-roller d, to the latter, substantially as specified.
3. In combination with the felting-boards and aprons G, the treadles h, for effecting the delivery of the goods from the bath, essentially as described.

WM. B. LODGE,
HIRAM PLATNER.
